W. H. Tracy, Attorneys,

UNITED STATES PATENT OFFICE.

JACOB BABST, OF CRESTLINE, OHIO, ASSIGNOR TO THE BURCH PLOW WORKS COMPANY,
OF CRESTLINE, OHIO, A CORPORATION.

SURFACING-MACHINE.

1,291,361.

Specification of Letters Patent.

Patented Jan. 14, 1919.

Application filed September 6, 1917. Serial No. 190,075.

To all whom it may concern:

Be it known that I, JACOB BABST, a citizen of the United States, residing at Crestline, in the county of Crawford and State of Ohio, have invented certain new and useful Improvements in Surfacing-Machines, of which the following is a specification.

My invention relates to new and useful improvements in surfacing machines and 10 more particularly to road building machines of the type in which the surfacing material, such as gravel, slag or crushed stone is discharged from a truck as the truck is drawn along the road and uniformly spread over 15 the road. More particularly my present invention is an attachment for a road building machine of the type shown in a patent to R. M. Myers, 1,233,107, patented July 10, 1917. The primary object of my invention 20 resides in the provision of an attachment for a road building machine of the character there shown which may be adjusted at will to vary not only the depth at which the material will be distributed but also the width 25 of surface over which the material will be distributed.

A still further object of my invention is to construct a spreader attachment for the road building machine of such a character 30 that initial spreading of the material employed may be accomplished by the road building machine and secondary adjustable spreading of the material may be thereafter performed by the spreader.

With these and other objects in view, my invention will be more fully described, illustrated in the accompanying drawings and then specifically pointed out in the claims which form a part of this application.

40 In the drawings:

Figure 1 is a perspective view of my attachment in use;

Fig. 2 is a top plan view of the attachment;

45 Figs. 3 and 3^a together are a side elevation of my improved attachment, the road machine to which it is applied being shown in section;

Fig. 4 is a fragmentary sectional view 50 taken on the line 4-4 of Fig. 3.

Corresponding and like parts are referred to in the following description and indicated in all the views of the drawings by the same reference characters.

55 In order to insure a clear and accurate

understanding of my invention and its use I have illustrated it in connection with the road building machine previously referred to. In the drawings 10 indicates a dumping truck of any suitable character having a 60 tilting end gate 11, and 12 indicates as a whole the road building machine. This road building machine is fully described in the patent referred to and any detail explanation of it is, therefore, unnecessary. Primarily the machine comprises a hopper-shaped casing open at its top and bottom and supported at its front by wheels 13 and at its bottom by runners or shoes 14. This hopper or casing is connected by chains 15 to 70 the truck at any suitable point, such as to the rear axle 16 and is so proportioned and located that the contents of the truck will be discharged into it. The back wall of this casing is provided near its bottom with an 75 opening communicating with the opening of the bottom and extending throughout the length of the hopper and a vertically adjustable gate 17 is mounted upon the back wall to vary the height of this opening so as to 80 vary the depth of the layer of crushed stone or other material being spread which will be discharged during progress of the machine along the road.

Obviously, with a road building machine 85 of the character thus briefly described although the depth of the material being discharged may be adjusted there is no means for increasing the width of surface covered by the discharged material beyond the width 90 of the hopper. Furthermore, any tilting of the hopper due to its engaging against obstructions will, of course, vary the depth of the material being spread. My improved attachment is designed both to provide 95 means for increasing the width of the surface being treated, if desired and for insuring a more uniform spreading of the material at the desired depth.

Primarily my attachment includes a plow 100 indicated as a whole by the numeral 18, adapted to be connected at the rear of the hopper to be drawn behind the hopper and capable of being adjusted vertically and of also having its blades or wings capable of 105 being adjusted toward and away from each other. More specifically the attachment includes the side members, blades or wings 19 which at their forward ends have pivot ears 20 formed with eyes 21 encircling the verti- 110

cally disposed part of a pivot shaft 22 the lower end of which is extended across the open bottom of the hopper and formed with an upturned terminal 23 by means of which 5 it is connected to the inner face of the front wall of the hopper. A bearing bracket 24 secured to the upper portion of the rear wall of the hopper at the top serves to brace and hold the shaft 22 in place. This shaft is 10 located centrally of the width of the hopper and the blades or wings 19 diverge rearwardly from the hopper as best shown in Figs. 1 and 2. These blades or wings are preferably formed of wood, although metal 15 may be employed, and at their lower forward edges are provided with reinforcing strips 25 of sheet metal of suitable thickness so that they may not be unduly worn and splintered through engagement with the material being 20 spread.

Hinges 26 secured to the inner faces of the wings 19 near their free rear ends carry the sections 27 of a spacer brace 28 the abutting ends of which are formed with a series of 25 openings to adjustably receive bolts 29 or other suitable fastening means passed through clamping plates 30 engaging against the front and rear faces of the brace 28. Nuts secure these bolts in place so that 30 the brace as a whole may be adjusted in length to vary the distance between the rear ends of the wings and consequently vary the width of surface over which the material will be spread. Preferably hinges 31 se- 35 cured to the wings intermediate their length support sections 32 of a second spacer brace 33 of like construction the abutting ends of which are adjustably connected by bolts 34 passed through clamping 40 plates 35.

In order to facilitate vertical adjustment of the forward end of the plow upon the pivot shaft 22 I provide the bracket 24 with an arm 36 which pivotally receives one end 45 of a hand lever 37 to which is pivoted the upper end of a lifting link 38 in the form of a strap of metal the opposite end of which is secured to one of the eyes 21 by a bolt 39 or equivalent fastening device. This lever 50 is provided with a hand latch mechanism 40 which coöperates with a notched segment 41 either secured to or formed integrally with the bracket 24 so that the lever may be locked to temporarily support the forward 55 end of the plow at any desired elevation. Collars 42 are mounted upon the shaft 22 between certain of the pivot ears 21 and may be adjustably clamped upon the shaft by set bolts 43 so as to permanently lock the plow 60 against either downward or upward movement after it has once been adjusted. Because of this all strain, during use of the machine, is removed from the hand latch and segment 41.

65 As a means for supporting the rear ends

of the blades at the desired elevation I secure a triangular-shaped bracket 44 to the outer face of each blade or wing near its free end. These brackets carry vertically disposed bearings 45 which slidably receive 70 shafts 46 which at their lower ends have detachable shoes or runners 47. The bearings also carry arms 48 which pivot the ends of hand levers 49 which are connected by links 50 with hooks 51 upon collars 52 ad- 75 justably clamped upon the upper ends of the shafts by set bolts 53. Each hand lever has a latch mechanism 54 coöperating with a notched segment 55 also supported by the adjacent bearing 45 so that the blades may 80 be locked in adjusted position after being raised or lowered by the levers.

In order to prevent lateral swinging of the rear portion of the plow during use, such as might be occasioned by ununiform 85 feeding of material in front of the plow or by any inequalities of the surface over which the material was being distributed I provide braces 56. Each of these braces includes a tubular member 57 pivoted as shown at 58 90 to one of the brackets 44 and a member 58' telescoping with the first and pivoted as shown at 59 to the forward portion of the hopper 12. Set bolts 60 or equivalent means serve to secure the sections 57 and 58' of these braces in adjusted position, 95 adjustability of these braces being necessitated as the free ends of the blades are to be adjustable toward and away from each other. Obviously, in place of telescopic braces 56 100 105 braces of the type shown at 28 and 33 may be employed between the hopper and blades or instead of the type of braces shown between the blades I may employ telescopic braces such as those em- 110 ployed between the hopper and blades. In other words, I reserve the right to make any changes in details of construction, materials employed, and the like, which may fall within the scope of the appended claims.

From the foregoing description taken in connection with the drawings the operation of my attachment will be readily appreciated. Preferably the adjustable gate of the hopper is open to such an extent as to 115 discharge material at a thickness somewhat greater than the actual thickness finally desired, while the plow is supported so that the lower edges of its blades are at just the elevation above the ground necessary to secure the desired thickness of the surfacing material. The blades are adjusted toward and away from each other to insure spreading of the material over the desired width 120 of surface and the truck is then started to 125 cause discharge and spreading of the material contained therein.

If because of the type of material being spread the weight of the plow itself is not sufficient to hold it from riding upward 130

upon the material weights may be applied to the rear ends of the wings in any suitable manner. For instance, boxes of crushed stone may be seated upon the brackets 44.

5 Having thus described the invention, what is claimed as new is:

1. A road surfacing machine including a plow having rearwardly diverging wings, means for securing the plow behind a movable distributer, and braces connected to the plow and adapted for connection to the distributer to hold the plow against swinging movement.

15 2. A road surfacing machine including a plow having rearwardly diverging wings, means for securing the plow behind a movable distributer, braces connected to the plow and adapted for connection to the distributer to hold the plow against swinging movement, and means for adjusting the length of the braces.

25 3. A surfacing machine including a plow having diverging wings, means for attaching the plow to the rear of a movable distributer, means for adjusting the plow vertically to space it varying distances above the ground, means for adjusting the blades toward and away from each other, and braces secured to the blades and adapted for connection with the distributer.

30 4. A surfacing machine including a vertically disposed shaft having a lateral lower terminal adapted for attachment to a distributing machine, a bearing for the upper portion of the shaft adapted for attachment to the distributer, a plow having rearwardly diverging blades having pivot eyes at their forward ends encircling the shaft, means carried by the bearing bracket for adjustably raising and lowering the forward portions of the blades with respect to the ground, and means connected to the blades and adapted for connection with the distributer for holding the blades against 45 swinging movement.

45 5. A road surfacing machine including a plow having diverging wings, means for

attaching the plow to the rear of a movable distributer, and means connected with the said wings and adapted for attachment 50 to the distributer for bracing the plow against swinging movement.

6. A surfacing machine including a plow, means for attaching the plow to the rear of a movable distributer, means for adjustably elevating the forward end of the plow, and stop means coacting with said first mentioned means for locking the forward end of the plow against vertical movement in 55 opposite directions. 60

7. A surfacing machine including a vertically disposed shaft adapted for connection with a movable distributer, a plow engaging with the shaft, means for adjustably elevating the forward end of the plow, and means 65 upon the shaft for locking the forward end of the plow against vertical movement in opposite directions.

8. A surfacing machine including a plow having diverging wings, means for attaching the plow to the rear of a movable distributer, brackets projecting laterally from the rear extremities of said wings at the outer sides thereof, vertical bearing sleeves carried by the said brackets, shafts 70 slidable through said sleeves, shoes carried by the lower ends of the said shafts, collars adjustable upon the shafts, and means carried by the brackets and engaged with said collars 75 for shifting the shafts with respect to the said bearings to adjustably elevate the rear extremities of said wings. 80

9. A surfacing machine including a plow having diverging wings, means for attaching the plow to the rear of a movable distributer, brackets projecting laterally from the free extremities of said wings at the outer sides thereof, means mounted upon the said brackets for adjustably elevating the free ends of said wings, and braces 90 engaged with the said brackets for holding the plow against swinging movement. 95

In testimony whereof I affix my signature.
JACOB BABST. [I. S.]
